[57] CLAIM

The ornamental design for a floral box with insert, as shown and described.

DESCRIPTION

FIG. 1 is a top perspective view of a floral box with insert showing my new design;

FIG. 2 is a bottom and rear perspective view thereof;

FIG. 3 is a top perspective view of the insert shown separately for ease of illustration;

FIG. 4 is a bottom plan view of the insert shown separately for ease of illustration;

FIG. 5 is a side elevation view of the insert shown separately for ease of illustration, the opposite side view is identical;

FIG. 6 is an end view of the insert thereof, the opposing end being a mirror image of the end view shown; and,

FIG. 7 is an exploded perspective view of the floral box with insert.

The thickness shown is not an appreciable thickness.
